DESIGN FOR A COSTUME JEWELRY PIN

John Caianiello, New York, N. Y.

Application November 10, 1945, Serial No. 123,644

Term of patent 7 years

(Cl. D45—19)

To all whom it may concern:

Be it known that I, John Caianiello, a citizen of the United States of America, residing in the Borough of Queens, County of Queens, State of New York, have invented a new, original, and ornamental Design for a Costume Jewelry Pin, of which the following is a specification, reference being had to the accompanying drawing, forming part thereof.

Fig. 1 is a plan view of a costume jewelry pin showing my new design.

Fig. 2 is a side elevation of the costume jewelry pin shown in Fig. 1, as seen from the left.

Fig. 3 is a side elevation of the costume jewelry pin shown in Fig. 1, as seen from the right.

I claim:

The ornamental design for a costume jewelry pin, as shown.

JOHN CAIANIELLO.
